LAUNDRY FLATWORK FEEDER TRUCK

Roy M. Schultz, Chicago, Ill., assignor to David A. Freeman Corporation, Chicago, Ill., a corporation of Illinois

Application September 30, 1948, Serial No. 52,092

17 Claims. (Cl. 254—2)

1

This invention relates to a laundry feeder truck used for handling damp clothes and the like in commercial laundries, having a container of variable volume, as disclosed in the co-pending application of James Mulvihill, Serial No. 52,081, filed September 30, 1948, and, more particularly, to improvements in the controls for varying the volume of said container.

Because of the weight and volume of damp clothes carried by such trucks, it frequently becomes difficult for the operator to manually raise the floor of the container so that the clothes may be fed onto the adjacent dryer or pressing machine. Also the operator while removing the damp clothes from the truck must often stop and manually raise the bottom of the container to the desired height. These stoppages are time consuming and a nuisance to the operator particularly when he is operating the truck alone.

Thus, it is one of the objects of this invention to provide controls whereby the operator may readily vary the height of the container floor with a minimum of effort.

It is a further object of this invention to provide controls for varying the volume of the container which are readily accessible to the operator from either side as well as the ends of the truck.

It is a further object of this invention to provide controls which will enable the operator to raise the bottom of the container simultaneously while removing the damp clothes therefrom.

It is still a further object of this invention to provide controls which will expedite the handling of the clothes by the feeder truck during the cleaning operation and thereby reduce the cost of such an operation.

It is still a further object of this invention to provide controls for operating the feeder truck which are simple, yet sturdy in construction and effective in operation.

Further and additional objects will appear from the description, accompanying drawings, and appended claims.

In accordance with one embodiment of this invention, a feeder truck is provided comprising a movable frame having a pair of rotatably mounted, elongated reels disposed at either side of said frame; a flexible container having the sides thereof windably mounted on said reels; and means for actuating and controlling the rotation of said reels. The actuating and controlling means are regulated by the operator of the truck so that the bottom of the flexible container may be raised as the damp clothes are removed from the truck and fed onto the press-

2

ing or drying machine, thus eliminating the need for the operator to bend over and lift out the clothes from the bottom of the container.

For a more complete understanding of this invention, reference should now be had to the drawings wherein—

Fig. 1 is a fragmentary side elevational view of a hydraulically controlled feeder truck with the bottom of the container in its lowered position.

Fig. 2 is a fragmentary top plan view of the feeder truck shown in Fig. 1.

Fig. 3 is an end view of the feeder truck shown in Fig. 1 with the position of the hydraulic control system for raising the bottom of the container shown in dotted lines and a portion of the frame cut away to show the construction of the bottom of said container.

Fig. 4 is an end view of a pneumatically controlled feeder truck shown with the bottom of the container in its raised position and a portion of the frame cut away to show the construction of said bottom.

Fig. 5 is a fragmentary sectional view of the pump and the piston-cylinder assembly for the hydraulically controlled feeder truck shown in Fig. 3.

Fig. 6 is a fragmentary sectional view of the control valve for the pneumatically controlled feeder truck shown in Fig. 4 with a portion of the intake and exhaust ports shown in cross-section.

Fig. 7 is a diagrammatic view of an air-hydraulic control system for a feeder truck with the flow of the hydraulic fluid for raising the bottom of the container shown in full arrows and the flow of the hydraulic fluid for lowering said bottom shown in dotted arrows.

Fig. 8 is a side elevational sectional view of the air-hydraulic pump unit for the control system shown in Fig. 7.

Fig. 9 is a side elevational sectional view of the bleeder valve for the control system shown in Fig. 7.

Fig. 10 is a diagrammatic view of a modified form of an air-hydraulic control system showing the flow of the hydraulic fluid in full arrows for one setting of the reversing valve, wherein the bottom of the container is lowered, and the flow of the hydraulic fluid in dotted arrows for another setting of the reversing valve, wherein said bottom is raised.

Referring now to the drawings, a feeder truck 20 is provided adapted to handle wet clothes upon their removal from a washing machine 25 prior to being fed into a drying or pressing ma-

chine. The truck 20, in this instance, comprises a movable frame 22, a flexible container 24 mounted on said frame, and an actuating and control unit 26 for regulating the movement of the bottom or floor 27 of said container 24.

The frame 22 comprises a rectangular shaped base 28 at the four corners of the underside of which are rotatably mounted wheels or casters 29, 30 and 32 (only three being shown). To the narrow sides of the base 28 are fastened vertically extending end plates 34 and 36 which act as two sides of the container 24 disposed intermediate said plates. Rotatably mounted on the upper edge of the end plates 34 and 36 are a pair of elongated reels 38 and 40; one disposed at either side of said upper edge and extending from one plate to the other. The reels 38 and 40 are adapted to rotate in opposite directions. The means whereby the reels are caused to rotate will be discussed in detail later. At either side of the end plates 34 and 36 are provided bracing members 42 (only one shown in Fig. 1) which extend from one plate to the other and hold said plates in their spaced relationship.

The container 24 is flexible, constructed preferably of a durable fabric, plastic or rubberized material, and has its two sides 44 and 46 windably mounted on reels 38 and 40, respectively. The end plates 34 and 36, as heretofore mentioned, serve as the other two sides of the container. The windable sides 44 and 46 of the container are held in a substantially parallel vertical relationship by the spacer or floor board 48, which is rectangular in shape and rests on the bottom 27 of the container. The length of the spacer board is substantially the same as the space between the end plates 34 and 36. The vertical movement of the spacer board 48 is dependent upon the rotation of the reels 38 and 40 which, in turn, are controlled by the operator.

Hydraulic, pneumatic, or air-hydraulic means may be employed for actuating and controlling the rotation of the reels.

In the hydraulically or pneumatically controlled truck, pulleys 50 and 52 are fastened to the corresponding ends of the reels 38 and 40 and extend outwardly from the plate 34 as seen in Figs. 1-4. Intermediate said reel pulleys 50 and 52 and mounted on the lower portion of plate 34 is a piston-cylinder assembly 54. The piston 56 has its rod 58 extending upwardly from said assembly. Rotatably mounted on the free or exposed end of the rod are pulleys 60 and 62 which are disposed in a side-by-side relationship. The piston 56, rod 58, and pulleys 60 and 62 are adapted to move in a vertical plane.

Rotatably mounted by brackets 63 and 65 on end plate 34 and disposed at either side of assembly 54 are idling pulleys 64 and 66. The vertical movement of pulleys 60 and 62 is transmitted by means of belts 68 and 70 into a rotational movement of the reels 38 and 40, respectively. One end of belt 68 is wound around and secured to reel pulley 50 and the remainder of the belt is passed under idling pulley 64 and over pulley 60 and has its free end secured at 72, to the end plate 34. Belt 70, in a similar manner, cooperates with pulleys 52, 66, and 62 and is fastened at 74 to the end plate 34. Belts 68 and 70 are wound around reel pulleys 50 and 52 respectively in such a manner that the reels will rotate in opposite directions to one another.

In the hydraulically operated system, a pump 88 is provided for actuating the vertical movement of the piston 56 of assembly 54. The pump

88 is secured to the end plate 34 adjacent assembly 54 and comprises a housing 90 (Fig. 5) which is substantially filled with a hydraulic fluid 92, a bleeder valve 94, and a pump piston 96, mounted to reciprocate in cylinder 98. Cooperating with the piston 96 are an intake check valve 100 which allows the fluid 92 to be sucked into the cylinder 98, upon the upward stroke of the piston 96, and an outlet check valve 102 which allows the fluid to pass into the assembly 54 upon downward movement of the piston 96. Piston 96 is normally held in its upper position by coil spring 104. The stem 106 of piston 96 extends upwardly from the housing 90 as seen in Fig. 5. Bleeder valve 94 is positioned adjacent the pump piston 96 and has the stem 108 thereof likewise extending upwardly from the housing. The valve 94 is normally held in a closed position by coiled spring 110. The piston 96 and bleeder valve 94 are actuated by a disc 112, rotatably mounted on end plate 34 above the pump 88. The disc 112 is provided with a pair of diametrically opposed studs 114 and 116, which are secured to the face of the disc and are adapted to independently contact the stems of the pumping piston 96 or bleeder valve 94, respectively, depending on the rotation imparted to said disc.

The rotation of disc 112 is controlled by links 118 and 120 which are pivotally connected to said disc at points 122 and 124, respectively, which are diametrically opposed to one another and intermediate studs 114 and 116, as seen in Fig. 5. Links 118 and 120 are pivotally connected at their other ends to arms 126 and 128, respectively, of bell crank levers 130 and 132, which are pivotally connected at opposite sides to the base 28 of the frame. Extending longitudinally the length of the frame 22 and disposed at either side thereof are foot treads or rails 134 and 136 which are pivotally mounted on said frame, and connected at corresponding ends to arms 138 and 140 respectively of bell crank levers 130 and 132. From this linkage arrangement, it is apparent that the rotation of the disc 112 is dependent upon the direction of force applied to foot treads 134 and 136; thus a downward treading force exerted on either treadle will cause the piston 56 of the assembly 54 to be raised and the bottom 27 of the container 24 in turn to be raised, and upon an upward force exerted on the foot treadle the bottom of the container will be lowered.

In the pneumatically controlled truck shown in Fig. 4, the arrangement of the pulleys and belts, and the piston-cylinder assembly 54 is the same as that above described for the hydraulically controlled truck. The source of pneumatic power is independent of the truck 20 and a connecting nozzle 142 is provided at one side of the end plate 34 for ready connection to said pneumatic power source (not shown). It is apparent that with this type of truck it is necessary that the pneumatic power source be located in the vicinity of the presser or drying machine or any other place where the damp clothes are to be unloaded from the truck. Intermediate the connecting nozzle 142 and the assembly 54 and mounted on the distributing tube 143 joining said nozzle and assembly is a rocker-arm control valve 144. As seen in Fig. 6, the control valve 144 comprises an inlet or high pressure intake port 146, an outlet port 148 to assembly 54, and an exhaust port 150. Mounted within both the intake and exhaust ports are check valves 152 and 154, respectively. Both valves 152 and 154

are normally held in a closed position by springs 156 and 158 embracing the stems 160 and 162 of said valves. The stems 160 and 162 project upwardly from the ports and have the upper ends 164 and 166 thereof exposed. Pivotaly mounted on the control valve housing is a rocker arm 168 which is adapted to independently contact the upper ends 164 and 166 of stems 160 and 162, respectively, depending upon the point where force is applied to said arm. Thus the floor of the container may be readily raised by depressing valve 152, or lowered by depressing valve 154.

In Figs. 7 and 10, a modified arrangement for actuating and controlling the vertical movement of the piston 56 in assembly 54 is shown. In this instance, an air-hydraulic pump 170 is employed for forcing the hydraulic fluid into the cylinder chamber of assembly 54. As seen in Fig. 8, the pump 170 comprises a cylinder housing 172 having an air intake port 173 formed therein, a sleeve 174 slidably mounted within said housing, a hollow piston 176 adjustably mounted within said sleeve, and a hydraulic inlet port 178 and outlet port 180, and an air outlet port 182 formed in the head 184 of said housing. Sleeve 174 is provided with an elongated slot 186 formed in the periphery thereof and adjacent the air intake port 173 and having a transverse passage 187 at one end of said slot. Slot 186 and transverse passage 187 permit the air to pass from port 173 to port 188 formed in the head of piston 176 and then to the underside of the piston to force the sleeve and piston upwardly in the cylinder housing 172. The hollow piston 176 is adjustably held within sleeve 174 by means of a spring-pressed ball 190 disposed in the piston head and which cooperates with notches 192 and 194. To enable the air to force the piston and sleeve upwardly, spring-pressed ball 190 engages notch 192 as seen in Fig. 8, thus enabling the port 188 to register with passage 187. A spring 196 in the base 198 of the cylinder housing 172 overcomes the friction encountered by the piston and sleeve on starting their upward movement. The air from the intake port 173 continues to force the piston 176 and sleeve 174 upwardly in the housing 172 until the sleeve contacts a coil spring 200, provided at the top of the cylinder housing, and is thus cushioned against further upward movement while the inertia of the piston and the air pressure applied to the underside of the piston forces said piston to continue on its upward movement thereby causing the spring-pressed ball 190 to become disengaged from notch 192 and to slip into the upper notch 194. After the ball 190 is seated in notch 194, the piston 176 is buffed by spring 201 and is restrained from any further upward movement. Upon the shifting of ball 190 from notch 192 to 194, the air supply from intake port 173 through port 186, passage 187, and port 188 is shut off and port 188 registers with a by-pass slot 202, formed in the inside of sleeve 176, which in turn registers with a bleeder port 204 formed in the upper portion of piston head 176. Thus the high pressure air at the underside of piston head 176 is bled through port 188, slot 202, and bleeder port 204 and then out to atmospheric pressure through exhaust port 182 formed in the head 184 of the housing. Gravity and springs 200 and 201 then cause the piston and sleeve to drop down and, upon the sleeve contacting coil spring 196, its downward movement is retarded while the piston continues on its downward movement, thereby causing ball 190 to become unseated from notch 194 and to slip back into notch 192. The piston and sleeve

are then once again in the correct relative position for being forced upward by pneumatic pressure.

Projecting downwardly a substantial distance from the head 184 of the housing 172 and centrally disposed therein, is a hollow shaft 206. The lower end of shaft 206 is embraced by piston 176 and projects into a cylindrically shaped cavity 208 in said piston. Thus upon upward movement of piston 176, shaft 206 approaches the base 209 of cavity 208. However, shaft 206 never reaches the bottom of the cavity as the relative position of the piston and sleeve is changed, resulting in said piston and sleeve commencing their downward movement again. The upper end of shaft 206 is fastened to the head 184 of the housing and opens into the passage 210 connecting the hydraulic intake 178 and outlet 180 ports in said head.

Upon downward movement of piston 176 in housing 172, hydraulic fluid is sucked in at port 178, past ball valve 212, through shaft 206, and into cavity 208. Upon upward movement of piston 176, the hydraulic fluid in cavity 208 is forced through shaft 206, past outlet ball valve 214, and out through outlet port 180. The joint between shaft 206 and piston 176 is sealed by packing 216. A stop plug 218 is provided in head 184 of the housing for replenishing the hydraulic fluid if needed.

As seen in Fig. 7, the source of air supply for air-hydraulic pump 170 is controlled by a valve 220 mounted in the line 221 connected to intake port 173 of pump housing 172. By operating valve 220, the operator may raise the floor 27 of the container to the height desired so that the damp clothes may be easily removed from the truck and fed into the dryer or presser without fatigue to the operator. The downward movement of piston 56 in assembly 54 is controlled by a bleeder cock valve 222, which allows the hydraulic fluid to return to the reservoir 224 from assembly 54 so as to cause the floor 27 of container 48 to be lowered and positioned again to receive damp clothes. The reservoir 224 is mounted directly on frame 22 adjacent the end plate 34 thereof. Valve 222, as seen in Fig. 9, is conventional and comprises a housing 226 having an inlet 228 and outlet 230 port formed therein, and a threaded stem 232 adjustable within said housing. The operator of the truck may control the depth of the container by regulating the amount of oil bled from the chamber of the assembly 54 to the reservoir 224 through the bleeder valve.

As seen in Fig. 10, a slightly modified arrangement employing the pump 170 is shown for actuating the piston 56 in assembly 54. A reversing valve 234 is provided intermediate the pump 170 and assembly 54 having a rotor member 236 and stator member 238. Stator member 238 is provided with four symmetrically arranged ports A, B, C, and D, and the rotor member 236 is provided with a pair of substantially U-shaped passages 240 and 242. Upon the setting of rotor 236, shown in full lines, passage 242 joins ports A and D of stator member 238 and passage 240 joins ports B and C; with this setting the piston 56 of assembly 54 is forced downwardly and the floor 27 of the container 48 is lowered. Upon a quarter turn of the rotor 236 from that shown in solid lines, by means of a handle 244 mounted thereon, passage 240 joins ports A and B and passage 242 joins ports C and D and the piston 56 of assembly 54 is forced upward and the floor 27 of the container is raised. With this arrangement no reservoir for the hydraulic fluid is required.

Thus, it will be seen that controls for varying the volume of the container of the feeder truck have been provided which will greatly facilitate the handling of damp clothes regardless of their dampness during the cleaning operation so as to increase the efficiency and reduce the cost of such an operation.

While several embodiments of this invention are shown above, it will be understood of course that the invention is not to be limited thereto, since many modifications may be made, and it is contemplated, therefore, by the appended claims, to cover any such modifications as fall within the true spirit and scope of this invention.

I claim:

1. In a device of the class described having a supporting frame, a pair of substantially parallel reels rotatably mounted on said frame, a container of pliable material having its sides windable on said reels, and means mounted on said frame for controlling the rotation of said reels; said means comprising pulleys mounted on corresponding ends of said reels, a piston-cylinder assembly to actuate said pulleys, the piston of said assembly having a rod, the free end of which extends from said assembly, a second set of pulleys arranged in a side by side relationship and mounted on the free end of said piston rod, idling pulleys disposed on opposite sides of said assembly, and a pair of flexible members cooperating with all of said pulleys and adapted to cause the sides of said container to be wound on or unwound from said reels upon movement of said piston.

2. In a device of the class described having a portable frame, a pair of substantially parallel elongated reels rotatably mounted on said frame, a container of variable volume suspended from said reels, and means mounted on said frame for controlling the volume variations of said container; said means comprising pulleys mounted on corresponding ends of said reels, a piston-cylinder assembly intermediate said pulleys, the piston of said assembly having a rod the free end of which extends from said assembly, a second set of pulleys arranged in a side by side relationship and mounted to move with said piston rod, idling pulleys disposed on opposite sides of said assembly, and flexible members cooperating with all of said pulleys, one of said flexible members having one end wound around one of said reel pulleys and passing under one of the idling pulleys and over one of said pulleys movable with said piston and having the other end fastened to said frame, the other flexible member similarly co-operating with the other pulleys, said flexible members adapted to cause said reel pulleys to rotate in opposite directions upon movement of said piston.

3. The device claimed in claim 1 in which said control means comprises a hydraulic pump unit mounted on said frame and adjacent said assembly, having the stems of the pump piston and the release valve for said pump unit extending upwardly therefrom and adjacent to one another, a disc rotatably mounted on said frame and adapted to independently contact said stems, a treadle pivotally mounted on said frame and extending substantially the length thereof, and a link member fastened at one end to said disc and fastened at the other end to said treadle; the direction of rotation of said disc being dependent upon the direction of force applied to said treadle.

4. The device claimed in claim 1 in which said

control means comprises a hydraulic pump unit mounted on said frame and adjacent said assembly and having the operating controls for said unit projecting upwardly therefrom, a control disc rotatably mounted on said frame and having a pair of transversely mounted studs, diametrically opposed, projecting therefrom and adapted to contact said operating controls, an actuating member pivotally mounted on each side of said frame and extending substantially the length thereof, and link connections between said actuating members and points on said disc diametrically opposed to each other.

5. The device claimed in claim 1 in which said control means comprises a source of pneumatic power adapted to be connected to said frame, tubing mounted on one end of said frame for distributing said pneumatic power to said piston-cylinder assembly, and a control element mounted on said tubing intermediate said source and assembly for regulating movement of said piston in said assembly.

6. The device claimed in claim 1 in which said control means comprises a source of pneumatic power adapted to be connected to said frame, tubing mounted on one end of said frame for distributing said pneumatic power to said piston-cylinder assembly, and a control element mounted on said tubing intermediate said source and assembly for regulating movement of said piston in said assembly; said control element comprising an inlet port having a one-way valve mounted therein, an exhaust port having a one-way valve mounted therein, an outlet port to said assembly, intermediate said inlet and exhaust ports, and a control lever pivotally mounted on said element and adapted to independently actuate said valves depending upon the point at which force is applied to said lever.

7. In a device of the class described having a portable truck body, an expandable and contractible container carried by said body, means for expanding and contracting said container including reel means rotatably mounted on said body for winding thereonto and unwinding therefrom the material of said container, and means for operating said reel means; said operating means comprising elongated substantially parallel foot operated treadle bars operatively connected to the reel means and pivotally mounted on said body, said bars being disposed on opposite sides of said container.

8. In a device of the class described having an upright supporting frame provided with a pair of parallel elongated reels rotatably mounted thereon and being disposed in spaced relation on said frame, an expandible open top container having substantially vertically extending sides windably mounted on said reels, and means mounted on said frame for effecting rotation of said reels; said means comprising a piston-cylinder assembly mounted on said frame intermediate said reels and having a portion of the reciprocating piston exposed and operatively connected to said reels to effect rotation of the latter; an air-hydraulic pump mounted on said frame adjacent said assembly for effecting reciprocation of said piston, and a control device adjacent the open top of said container for actuating said pump.

9. The device claimed in claim 8, in which said air-hydraulic pump comprises a housing unit, a source of air pressure for said unit, a source of hydraulic fluid for said unit, a sleeve slidably mounted within said housing, a hollow

piston adjustably held within said sleeve, both said sleeve and piston responsive to air pressure, and means for expending hydraulic pressure from said unit upon response of said sleeve and piston to said air pressure; said piston when in its starting position relative to said sleeve, adapted to cause certain ports and passages in said housing, sleeve, and piston to register and thereby cause said sleeve and piston to be responsive to air pressure, and when in another relative position to said sleeve to cause certain ports and passages in said housing, sleeve, and piston to register and allow the sleeve and piston to resume its original starting position.

10. In a device of the class described having a movable supporting frame provided with a pair of elongated reels rotatably mounted on opposite sides of said frame, a container having flexible side portions windably mounted on said reels, and means for actuating said reels, said means comprising a pressure-responsive element reciprocally mounted on said frame, an operative connection between said element and said reels whereby the reciprocatory movement of said element effects rotational movement of said reels in opposite directions with respect to one another, and a manually operable pressure-regulating unit mounted on said frame and operatively connected to said element.

11. In a device of the class described having a movable supporting frame provided with a pair of spaced rotatably mounted reels, an expandable and contractible container windably mounted on said reels, and means for actuating said reels and effecting expansion and contraction of said container; said means comprising an actuator mounted on said frame adjacent one end of said reels, a pressure-responsive reciprocating element mounted within said actuator and having a portion thereof exposed, an operative connection between the exposed portion of said element and the adjacent ends of said reels whereby the reciprocatory movement of said element effects rotational movement of said reels, and a pressure control unit mounted on said frame and operatively connected to said actuator for regulating the reciprocation of said element.

12. In a device of the class described having an upright portable truck body, a pair of spaced substantially parallel reels rotatably mounted on said body, an expandable and contractible container suspended from and disposed between said reels and having the sides of said container windably mounted on said reels, a rigid substantially flat vertically adjustable bottom element positioned within said container and effecting substantially vertical disposition of the sides of said container mounted on said reels, and means operatively connected to said reels for effecting rotation thereof; said means comprising a pneumatically operated actuator mounted on said body adjacent one end of said reels and being operatively connected thereto, and manually operated valve means mounted on said body and communicating with said actuator for controlling the operation of said actuator.

13. In a device of the class described having an upright frame, a pair of spaced substantially parallel elongated reels rotatably mounted on said frame, a continuous pliable web suspended from and disposed between said reels and having the opposite edges of said web windably mounted on said reels, a non-flexible bottom element subtended by said web and disposed between said reels to form a container having a substantially

horizontal bottom and substantially vertical side portions, and means for rotating said reels to effect height-adjustment of said bottom element; said means comprising a pressure-responsive piston member mounted for reciprocatory movement on said frame adjacent one end of said reels and being operatively connected to said reel ends whereby the reciprocatory movement of said piston member effects rotary movement of said reels, and a manually operable pressure-transmitting control mounted on said frame and operatively connected to said piston member to effect reciprocatory movement thereof.

14. In a device of the class described having a frame, a pair of substantially parallel elongated reels rotatably mounted on said frame and disposed in spaced relation with respect to one another, a pliable container suspended from and disposed intermediate said reels and having the sides thereof windably mounted on said reels, and means for effecting rotation of said reels; said means comprising a fluid-operated reciprocating piston member mounted on said frame and operatively connected to said reels for imparting rotational movement thereto upon reciprocation of said piston member, a source of fluid supply, and a fluid pump communicating with said supply and piston member, said pump including means for controlling the rate of return flow of said fluid from said piston member to said supply and thereby lengthen the windable sides of said container.

15. In a device of the class described having an upright frame, a pair of spaced substantially parallel elongated reels rotatably mounted on said frame, a pliable container suspended from and disposed intermediate said reels and having substantially vertically extending side portions windably mounted on said reels, and means mounted on said frame for rotating said reels; said means comprising a fluid-operated reciprocating piston member for use with a source of fluid under pressure and mounted on said frame adjacent one end of said reels and operatively connected to the latter whereby the reciprocatory movement of said piston member effects rotatable movement of said reels, and a manually operable control mounted on said frame and disposed intermediate and communicating with said piston member and fluid source for controlling the rate of flow of fluid between said piston member and said supply and thereby vary the length of said vertically extending side portions.

16. In a device of the class described having a portable truck body, an expandable and contractible container carried by said body, means for expanding and contracting said container including reel means for winding thereonto and unwinding therefrom the material of said container, and means for operating said reel means, said operating means comprising a pneumatically-operated actuator, and manually operated valve means for controlling the flow of air to said actuator, said manually-operated valve means comprising a valve housing having an inlet port adapted to be connected to a source of pneumatic pressure, an outlet port connected to the actuator, and an exhaust port, said inlet and exhaust ports having check valves mounted therein, and a control lever rockably mounted on said housing for regulating said check valves.

17. In a device of the class described having a supporting frame provided with a pair of elongated reels disposed at either side of said frame, an expandable container having the sides thereof

11

windably mounted on said reels, and means mounted on said frame for actuating said reels, said means comprising a piston-cylinder assembly mounted on said frame intermediate said reels and having the piston thereof reciprocatory, an air-hydraulic pump mounted on said frame adjacent said assembly for actuating said piston, a control device for said pump, said air-hydraulic pump comprising a housing unit, a source of air pressure for said unit, a source of hydraulic fluid for said unit, a sleeve slidably mounted within said housing, a hollow piston adjustably held within said sleeve, both said sleeve and piston responsive to air pressure, and means for expending hydraulic pressure from said unit upon response of said sleeve and piston to said air pressure.

ROY M. SCHULTZ.
